UNITED STATES PATENT OFFICE.

SIMON DE LA PENA, OF CENTRAL, NEW MEXICO.

BLACKSMITH'S ANVIL.

1,361,311.

Specification of Letters Patent.

Patented Dec. 7, 1920.

Application filed May 15, 1917. Serial No. 168,813.

To all whom it may concern:

Be it known that I, SIMON DE LA PENA, a citizen of the United States, residing at Central, in the county of Grant, State of New Mexico, have invented certain new and useful Improvements in Blacksmiths' Anvils; and I do hereby declare the following to be a full, clear, and exact description of the invention such as will enable others skilled in the art to which it appertains to make and use the same.

This invention relates to anvils and particularly to attachments for anvils.

As is well known to those skilled in the art, there are a great many tasks to be performed at the anvil that require much mechanical skill and many of them requiring the services of two operators. Among these tasks may be included the making of welds, 20 punching, bending and shaping. Many require the use of special tools and it is the object of the present invention to enable the unskilled mechanic to perform many of these tasks that could otherwise be performed only 25 by a skilled operator and furthermore to enable the performance of many tasks by a single operator that might otherwise require two.

In carrying the invention into effect, there 30 is employed a main body member having a shank that is passed through the "hardy" hole and which serves to hold the body member in place upon the face of the anvil. When a supplemental plate is to be used 35 jointly with the body member between it and the anvil, the shank will serve to hold both the body and the plate in position and it is provided with means for clamping it tightly.

40 Referring to the drawings:

Figure 1 is a perspective view of a portion of the device in its detached position,

Fig. 2 is a perspective view of a portion of the device attached to the anvil,

Fig. 3 is a perspective view of another form of the device attached to the anvil,

Fig. 4 is a perspective view showing one use of the device when attached to the anvil,

Fig. 5 is a detail view of one of the plates 50 of the attachment,

Fig. 6 is a detail view of another plate,

Fig. 7 is a detail view of still another plate, and

Fig. 8 is a detail view of a punching 65 mechanism used in connection with the pres-

ent invention and shown in position in Figs. 1 and 2.

Referring more particularly to the drawings, the reference character 10 designates an anvil, the upper face of which is provided with a rectangular opening, common to all blacksmiths' anvils.

Referring to Fig. 1, the number 11 designates the body member which is a plate or block, whose upper face is provided with a transverse groove 12, semi-circular in cross section, and a transverse groove 13, semi-circular in cross section, which groove is adjacent the transverse groove 12 but of a different size for a purpose to be herein-after described. Extending downwardly through the member 11 are rectangular slots 14 and 15 near one end thereof, and near the other end a slot 16 is provided, while extending downwardly through the transverse grooves 12 and 13 are circular openings 17. The under face of the member 11 is provided with transverse grooves 18, 19 and 20 which are semi-circular in cross section and are of different dimensions, and between the semi-circular grooves 18 and 19 is an angular groove 21. One end of this member or block is cut out as at 22 to form upper and lower spaced jaws 23, and passing through the upper jaw 23 are a series of perforations or openings whose upper ends are counter-bored or enlarged to produce tool guides or recesses 24. Secured to the block adjacent the jaws 23 is a yoke or guide member 25, the upper portion of which is provided with perforations 26 through which pass punching elements 27 whose lower ends enter the perforations 24 in the upper jaw 23. This yoke member 25 is secured in place by the depending legs 28 having inturned feet 28' clamped beneath the body member 11.

Depending from under the face of the member 11 is a shank 29 which is slotted as at 30 and adapted to pass through said slot 30 is a wedge 31, and embracing the squared shank 29 is a squared washer 32, said washer resting on the upper edge of the wedge 31. Thus is produced a straining means for drawing the body member down toward the anvil and clamping another member beneath it.

As shown in Fig. 1 a lower member or base plate 34 is adapted to be used in connection with the member 11, said plate having semi-circular transverse grooves 35, 36

and 37 and an angular transverse groove 38. This plate member is provided with a squared opening near one of its ends adapted to receive the squared shank to secure the plate in place between the jaw member 11 and the top face of the anvil, and when it is in this position its semi-circular transverse grooves 35, 36 and 37 coincide with the semi-circular transverse grooves 18, 19 and 20 to form circular openings of different diameters, and the angular transverse groove 21 and the angular transverse groove 38 form a squared opening. The base member corresponds substantially with the shape of the body member or block although it is preferably thinner.

The rectangular openings 14, 15 and 16 and the circular openings 17 are adapted to receive the shanks of any of the small anvil tools commonly used in connection with anvils, the shanks of said tools being merely inserted in these openings as desired.

In Fig. 2, the device is shown as operating as a punch only, and it will be seen that by impact of a hammer upon the punching elements 27, the same are caused to engage a strip of metal or other piece of work which is passed between the jaws 23, thus perforating the strip as will be understood. It is to be understood, of course, that the punches 27 may be of various sizes and shapes as desired.

In Fig. 3, the punching device is removed, and a base plate such as that shown in Fig. 1 is inserted between the member 11 and the anvil 10, and as shown by the reference character 42 a strip of metal is inserted between the end extension 43 of the member 11 and the end extension 44 of the plate 34 and the strip bent as at 46 by impact of a hammer upon the opposite sides of the extension 44. Another strip 45 separates the members at the other end. These strips constitute "spacers," and when employed they enlarge the openings produced by the registering grooves described.

In Fig. 4, the device is shown as used for welding together the ends of metal strips 50 and 51. In this illustration the member 11 alone is used.

In Fig. 5 a top member or facing 70 is shown, and from said plate projects a rectangular tongue 71 which is adapted to be received in the opening 14 of the member 11 to retain the plate 70 in place thereon, and said plate is provided with a plurality of circular openings 72, a rectangular opening 73 and a circular opening 74 by means of which various operations may be carried out when the device is in place on the anvil. This plate 70 also has an extension 75 which is provided with a rectangular opening 76 which is adapted for alinement with the opening 16 in the body member. The facing

plate may be reversed end for end and its tongue 71 inserted in the opening 15.

In Fig. 6 is shown an extra base plate 60 which is provided with rectangular openings 61 and 62 near one end, and near its other end with rectangular openings 63 and 64 and other openings 65 and 66 of different sizes. The rectangular opening 62 is adapted to receive the depending shank 29 to secure the plate in place on the anvil.

In Fig. 7 is shown another extra base plate 77 provided with a circular opening 78, a rectangular opening 79, a pair of spaced rectangular slots 80, and a plurality of circular openings 81, 82, 83, and 84. In securing this plate 77 to the anvil, the rectangular shank 29 is adapted to pass through the rectangular opening 79, and either extra plate is clamped between the member 11 and the top face of the anvil 10 by setting up the wedge or otherwise actuating the straining means employed. These extra base plates purposely omit the end extensions 44 and 75 so as to leave clearance under the opening 16, and beyond their shank openings 62 and 79 they are shorter to their remote ends than is the base plate 34, so that when used beneath the body, with or without said plate 34, there is clearance below the openings in this end of the body also. The openings in these extra plates, other than those for the shank, are disposed to aline with the various upright openings in the body and the base plate; and the same may be said of the openings 100 in the facing plate 70, although this plate is held accurately upon the body by the tongue rather than the shank. It will be clear to those familiar with this art that, while the openings in the superposed members are in axial alinement, they are not necessarily of the same size excepting those which are to closely receive the shank or the tongue. The obvious purpose is to permit the introduction and use of various tools in these openings, and the members containing the latter serve in different capacities according to their arrangement.

As an illustration, let us assume that a punch is to be employed whose shank is 115 round and perhaps a half inch in diameter while its bit is a quarter inch square. Such a tool could not be passed down through one of the openings 17 to perform punching in an underlying groove 38 or 36 in the base 120 plate 34, and accordingly an extra plate such as that numbered 60 would be clamped under the body with its quarter inch square opening 64 serving as the female die to coact with the square bit, while the circular 125 opening 17 above it would serve as the guide for the shank of this tool. As another illustration, hand dies and punches are tools whereof each is mounted on its own handle and held by the operator while 130

he strikes a blow on the tool. In this case the facing plate 70 might be used, and its openings 72 constitute female dies of a variety of sizes.

- 5 Referring to Fig. 8 it will be seen that the upper jaw 23 is provided with a plurality of spaced recesses 24 as heretofore stated, and mounted in these the openings 26 of the yoke are the shanks of the punch elements 27. Each shank has at its lower end a reduced cutting portion or bit 55 and surrounding the same is a coil spring 56 resting on the bottom of the recess 24 to provide means for resiliently mounting the 10 punching elements 27. These members are further provided with cross pins 58 or the like which prevent them flying out of the yoke member under the influence of said coil springs.
- 15 20 From the foregoing it will be seen that the present invention provides means by which a blacksmith's anvil together with its several attachments and devices may be used by one not skilled in the use thereof, and permits of an unskilled person readily accomplishing the different operations which only those familiar with the blacksmithing trade could perform without the 25 use of these attachments.
- 20 30 Having thus described the invention, what is claimed is:

1. An attachment for anvils comprising a body provided with a plurality of forming surfaces and having a depending shank 35 adapted to pass through the "hardy" hole of an anvil, said shank having means for drawing and holding it through the "hardy" hole, and a coöperating plate having an opening to receive the shank and 40 forming surfaces arranged for coöperation with corresponding surfaces of the body.
2. An attachment for anvils comprising a body provided with a plurality of open-

ings and having a shank adapted to pass through the "hardy" hole of an anvil, 45 straining means for drawing the shank downward and the body toward the anvil, and a coöperating member clamped between said body and anvil by said means and having openings adapted to aline with those 50 in the body at this time, for the purpose set forth.

3. An attachment for anvils comprising a body having a depending shank adapted to pass down through the "hardy" hole of 55 an anvil, means for drawing said shank downward, a coöperating plate having an opening to receive the shank, and a coöperating member having retaining elements removably disposed between the body 60 and plate and adapted to be clamped thereby, said body, plate, and member having openings adapted to aline at this time, for the purpose set forth.

4. An attachment for anvils comprising 65 a body provided with a plurality of forming surfaces and having a depending shank adapted to pass down through the "hardy" hole of an anvil, means for drawing said shank downward, a coöperating plate having 70 an opening to receive the shank and forming surfaces arranged for coöperation with corresponding surfaces of the body, and a coöperating member having a retaining finger removably disposed between the 75 body and plate and adapted to be clamped thereby, said body, plate, and member having openings adapted to aline at this time, for the purpose set forth.

In testimony whereof, I affix my signature, in the presence of two witnesses.

SIMON DE LA PENA.
